The ornamental design for a sensor plate for a fingerprint identifying machine, as shown and described.

DESCRIPTION

FIG. 1 is a perspective view of a sensor plate for a fingerprint identifying machine showing our new design;

FIG. 2 is a perspective view thereof in the using condition;

FIG. 3 is a top plan view thereof;

FIG. 4 is a left side elevational view thereof;

FIG. 5 is a front elevational view thereof; and,

FIG. 6 is a right side elevational view thereof.

The base portion thereof shown in broken lines in FIGS. 1-6 and the hand portion shown in FIG. 2 are for illustrative purposes only and form no part of the claimed design.
